GARMENT HANGER

Peter M. Steenland, Palisades Park, N. J.

Application February 12, 1941, Serial No. 378,529

1 Claim. (Cl. 24—237)

My invention relates to improvements in "garment hanger." In the past all garment hangers are so constructed that the least bit of bumping into, or knocking, of said hangers they fall from the rod from which they are suspended and litter the closet, or on a clothing store or garment factory, they become dangers to the shoppers or workers, who might trip, or fall, over said hangers. Those hangers also cause the hiring of extra help in department stores to keep picking the hangers from the floor to avoid accident and to keep the store or factory neat and tidy. With my invention the hanger when once placed upon the rod will stay there and cannot be knocked, or bumped off the rod from which they are suspended. In my hanger I take advantage of a spring arrangement with a hook opening slightly less than the thickness of the hanging rod thus giving the hanger a snapping arrangement, or effect, as is more particularly hereinafter described. Another advantage of my hanger is that it is an inexpensive proposition to make and is simple in construction and to use. It makes the cheapest, most inexpensive and simple hanger upon the market and fills a long felt need in respect to hangers and does away with extra help in stores and factories, now being used to pick up hangers, as they will not fall off the rod after once being placed thereon. That is true even when removing a garment from the hanger.

Some forms of my invention are illustrated in the accompanying drawing in which Figure 1 shows a front view of one type of garment hanger. Figures 2, 3 and 4 are fragmentary views of modified forms of garment hangers.

Reading more particularly on the drawing Figure 1 of my said invention, the hanger is designated 10, the hanger bar is 11, the hook portion is 12. Said hook portion consists of straight stem portion 13 and containing locking loop 14 and hook section 15 and end portion 16. Figure 1 also shows the hook, hooked onto the clothes bar 17.

The object of this invention being as previously stated to prevent the hook from pulling off the rod member 17. That is accomplished by having the space between the locking loop 14 and the end portion 16 smaller than the diameter of the rod 17 as heretofore indicated. In slipping the hook over rod 17 the locking loop 14

5 and the end portion 16 have to flex, as indicated in dash and dotted lines in Figure 1, so as to snap over rod 17 and therefore offer enough resistance to prevent the hook from pulling off the rack bar 17.

Figure 2 is a modification showing a semi-loop 18 instead of lock loop 14.

Figure 3 shows a type of hanger of the cheaper grade made out of a single piece of wire. The 10 stem portion is twisted as seen at 19. One of the wires is twisted to form a lock loop 20. The both wires are shaped to form the back portion 21 and twisted to a common end portion 22.

Figure 4 is another form of my invention made 15 out of a single piece of wire the difference is that the wires are clipped as shown at 23 and one end used to form a flexible loop 24 to snap over rod 17. The action of all three modifications are similar to the action described in Figure 1.

20 While I have illustrated my invention in different ways and using different materials and means, still I do not intend to limit myself to those particular means, designs, methods, or 25 materials, as it is apparent that other means, designs, methods and materials may be employed in obtaining the same results within the scope of any claim without departing from the scope or spirit of my invention.

30 I claim:

35 A garment hanger hook, as herein described, for use in connection with a supporting rod of known diameter consisting of a straight portion adapted to be connected to a hanger, and having 40 therein a complete inner circular loop merging into a hook shaped section extending about said inner loop and in substantially the same plane thereof, the section forming said hook being open at its extremity opposite the completed inner circular loop and the distance between the inner circular loop and the extremity of the hook being slightly less than the diameter of the supporting rod, whereby when said open hook portion 45 is forced open by said rod a direct spring action between the open end of said hook and the inner circular coil forming said complete inner circular loop results to prevent the hook from becoming accidentally disengaged from the rod.

PETER M. STEENLAND.
